UNITED STATES PATENT OFFICE

FRANK B. ALLEN, OF LOWER MERION TOWNSHIP, PHILADELPHIA COUNTY, PENNSYLVANIA, ASSIGNOR, BY MESNE ASSIGNMENTS, TO THE ALLEN-SHERMAN-HOFF COMPANY, OF PHILADELPHIA, PENNSYLVANIA, A CORPORATION OF PENNSYLVANIA

FURNACE ASH GRINDER AND REMOVER

Application filed May 19, 1928. Serial No. 279,103.

This invention relates to an improved apparatus for breaking and handling solid material and more particularly incombustible residues from a furnace.

5 It has been customary in removing the incombustible residues from furnace bottoms to drop the same into a conduit containing water, the coarse material having first been separated from the fine material between the 10 furnace bottom and the conduit and the larger pieces broken up or else removed. This procedure has necessitated the subsequent handling of the coarse, solid material manually or by clamshell buckets and the like, 15 and has not resulted in a sufficiently finely divided mass of solid material to be disposed of readily and completely through an impeller pump as is often desirable.

My invention aims to provide a power 20 serving apparatus for reducing ash as ordinarily encountered in furnace hoppers to the size required for passage through an impeller pump.

It relates also to a portable ash grinder and 25 means for employing the same with a plurality of hopper discharge openings and an ash handling fluid conveyor.

Referring particularly to the drawings:

Fig. 1 is a longitudinal section through one 30 form of device embodying my invention and showing the grinding mill in side elevation.

Fig. 2 is a transverse section taken upon the line 2—2 of Fig. 1.

In its preferred embodiment the device 35 comprises a furnace hopper having the side walls 1 and the end walls 2 and provided with a plurality of transversely extending cracks 3 in its bottom which cooperate with the side and end walls to direct the discharge 40 of incombustible residues through a series of discharge openings. The discharge openings are closed by the movable gates 4. A plurality of toothed grinding rolls 5 may be suitably mounted in the hopper for rotation 45 therein, whereby incombustible residues may be ground to a certain size before being dropped to the bottom of the hopper.

A portable grinding mill is adapted to be disposed beneath the hopper upon the base- 50 ment floor of the boiler house. The grinding

mill comprises a receptacle 8 suitably mounted upon wheels. The receptacle extends outwardly of the hopper and upwardly beyond the position of rest of solid materials banked between the receptacle and hopper. A plurality of toothed grinding wheels 9 are mounted within the receptacle, and are driven in rotation by the motor 10 through the train of connections illustrated. These grinding wheels break up the incombustible 60 residues to a size smaller than that effected by the grinding wheels 5 and sufficiently small for the residues to be washed through a conduit.

A conduit 14 is disposed in the floor and 65 extends beneath the discharge openings of the hopper. The surface of the floor slopes toward the conduit as can be clearly seen in Fig. 2. Rails 15 to support the grinding mill are sunk in the sloping section of floor on 70 opposite sides of the conduit. The upper surfaces of the rails 15 are substantially flush with the surface of the floor so that residues falling upon the floor can be washed by water down the sloping surface of the floor into 75 the conduit. Openings are provided in the upper surface of the conduit 14 in alignment with the discharge openings of the hopper, the walls of the openings carrying a grate 16 adapted to prevent the entrance of residues 80 too large to be washed through the conduit 14. Water or other liquid is introduced into the conduit through a pipe 18.

The mixture of residues and water flows 85 through the conduit to a sump tank 20. A grate 21 positioned at the entrance to the tank permits finely divided residues and water to flow therethrough into the tank. The grate 21 is inclined at an angle so that residues too coarse to pass through the grate 90 are directed to a plurality of grinding rolls 22 mounted for rotation in the tank. These grinding rolls are adapted to break up the residues to a sufficiently small size, so that the entire mass of residues can be passed 95 through an impeller pump 23. The residues are pumped through the pipe 24 to a storage tank 25.

In the operation of the device the incombustible residues drop through the furnace 100

hopper between the grinding rolls 5 where they are broken into coarse particles and accumulate upon the gates 4 in the bottom of the furnace hopper. The portable grinding mill is moved manually or otherwise to a position in alignment with one of the discharge openings, the corresponding gate 4 is opened and the residues are dropped into the receptacle 8. The grinding wheels 9 are rotated breaking up the residues to a size sufficiently small that they can be flushed by the water through the conduit 14. This operation is repeated alternately at the other discharge openings of the ash hopper. As the mixture of water and broken residues passes from the conduit 14 the finely divided residues drop directly into the tank 20 while the coarser particles are propelled on to and further broken up by the rolls 22 to a condition suitable to be passed through an impeller pump after which the entire mass of residues and water is pumped into the storage tank 25.

While a particular embodiment of the invention has been herein described, it will be apparent that modifications can be made therein without departing from the spirit of the invention, and it is not desired to limit the scope of the invention otherwise than is indicated by the accompanying claims.

What I claim is—

1. In apparatus for handling solid materials, the combination of a hopper having a series of discharge openings, movable gates for the openings, a conduit extending beneath the series of openings, a grinding mill mounted for movement longitudinally of the conduit having an inlet opening adapted to be disposed in alignment with each discharge opening in turn and having an outlet opening adapted to direct the broken materials into the conduit, and a receptacle mounted on said grinding mill and having walls extending upwardly and outwardly from said inlet opening to a point beyond the position of rest of solid materials banked between the receptacle and hopper.

2. In furnace construction, a floor, a hopper disposed in spaced relation above the floor, said hopper being provided with a series of discharge openings, movable gates for the openings, a grinding mill mounted for movement between the floor and hopper and including a receptacle adapted to receive the residues discharged through the discharge openings and an outlet opening for the broken residues, said receptacle having walls extending upwardly and outwardly from said inlet opening to a point beyond the position of rest of solid materials banked between the receptacle and hopper, and a conduit in the floor extended beneath the series of discharge openings adapted to receive the residues discharged from the outlet opening and to conduct them to a place of disposal.

3. In furnace construction, a floor, a hopper disposed in spaced relation above the floor and provided with a series of discharge openings, movable gates for the openings, rails in the floor substantially flush with the surface of the floor, a grinding mill including a receptacle adapted to be moved along the rails into successive alignment with the discharge openings of the hopper to receive the incombustible residues discharged therefrom, means for breaking up the residues in the receptacle, the receptacle being provided with an outlet for discharge of the broken residues, and a conduit in the floor extending beneath the discharge openings between said rails and adapted to receive the residues discharged from the outlet, and to conduct them to a place of disposal.

4. In apparatus for handling solid material, a hopper provided with a discharge opening, a receptacle adapted to receive the solid material discharged from the opening, said receptacle extending outwardly of the hopper and upwardly beyond the position of rest of solid materials banked between the receptacle and hopper, means in the receptacle adapted to break up the solid material, said receptacle being provided with an outlet, a conduit adapted to receive the broken solid material discharged from the outlet and to contain fluid means for conducting the broken solid material through the conduit.

In testimony whereof I hereunto affix my signature this 3rd day of May, 1928.

FRANK B. ALLEN.
